LIQUID SPRAYER

Frederick W. Lohse, Attleboro, Mass., assignor
to T. J. Holmes Company, Inc., Norton, Mass.,
a corporation of Massachusetts

Application June 22, 1936, Serial No. 86,461

1 Claim. (Cl. 221—85)

This invention relates to liquid sprayers of the general type used for spraying liquids upon windows, house plants, clothing and for other purposes and is intended to provide simple and effective means for economically performing its functions while also making provision for convenient and safe transportation when filled, or partly filled, with liquid without danger of leakage of the contents.

10 With these objects in view the invention comprises a bottle closure removably attachable to a bottle or other container and provided with a movable plunger piston and a liquid chamber, the closure being provided with removable sealing means which serves both to prevent leakage of the liquid content to the outside and to retain the plunger in a depressed position to avoid the filling of the outlet conduit which forms a hollow stem for the piston.

20 In the accompanying drawing I have illustrated embodiments of the invention to different forms of sprayer devices, in which—

Fig. 1 is a vertical section illustrating a container provided with my improvement, the sealing cap being removed and the plunger standing in its normal raised position.

Fig. 2 is a central section on a plane at right angles to Fig. 1 showing the upper part of the container with the plunger depressed by engagement with the leak-proof sealing cap.

30 Fig. 3 illustrates a modified form of piston chamber construction in which the coiled spring is placed outside of the piston chamber and above it, instead of inside and beneath the piston. The diameters of the piston stem and its bore are, for the sake of clear illustration, much exaggerated in comparison with actual practice.

In the practice of my invention according to the illustration in the drawing, A indicates a bottle or similar container having an externally threaded neck portion for the reception of an internally threaded closure or cap 1, which is provided with interior washer 2 and an exterior washer 3 around a central opening through which is inserted a central headed thread 4, whose head is externally threaded and whose inwardly projecting shank portion is threaded to receive a clamping nut 5.

The threaded plug 4 is provided with a smooth cylindrical axial bore and in this bore or passage is slidably mounted a close fitting hollow plunger stem 6. To the top of the plunger stem 6 is secured a spraying block having, in this case, a transversely bored passage for the reception of a hollow nozzle member 8, in which is inserted

an externally threaded plug to assist the spraying of the liquid but restricting its escape and giving it a whirling motion before it passes out through the very small nozzle opening 10. The sprayer block 7 is also provided with a diametrical groove or recess extending in the vertical plane of the spray nozzle, so that when the finger is pressed into this groove the spray points in the direction of the finger.

To render the sprayer safe for transportation in a trunk or container with other articles, which would be injured by leakage of the liquid, I provide a cup-shaped sealing cap 12 dimensioned to cover and overlap the sprayer head 7, the bottom or open end of the cap being internally threaded 15 to screw upon the threads 4a of the central member 4 of the closure cap. While a few drops of liquid may leak out of the nozzle under certain conditions, nevertheless it can not escape to the outside because the sealing cap, when screwed down tightly against the washer 3, forms a positive and reliable seal wholly preventing any possible escape of the liquid, either through the nozzle or through the joint between the central plug 4 and the closure.

A cylindrical piston 13 is secured to the lower end of the plunger stem 6 and, as shown, is provided with an internal valve chamber in which is mounted a check valve 15 in the form of a ball closing the central passage in the lower end of the piston when the piston moves to the top of the surrounding piston chamber 16 after the liquid has been expelled by the downward stroke. The object of the valve is to prevent weakening the partial vacuum in the piston chamber 16 created by the upward stroke of the pump and means is provided to prevent the check valve member 15 from closing the liquid outlet passage formed through the stem 6 in any suitable manner, as by means of an in-turned lip 14 40 at the lower end of the piston stem.

It will be observed that the piston or pump chamber is closed at the bottom and is surrounded by an elongated shell annularly spaced from the outside of the piston chamber. The piston chamber is also provided with inlet holes 16a immediately below the level of the bottom of the piston when the piston is in raised position. A helical spring 18 is seated upon the closed bottom of the pump chamber and exerts an upward pressure or thrust against the bottom of the piston. The outer shell 17 has its upper portion contracted to fit snugly around the open or upper end of the piston chamber 16 and has its upper portion in-turned to form an annular

flange 17^a, which closely fits around the piston stem and serves as a stop for the upward stroke of the piston.

When the piston is depressed by pressure of 5 the fingers upon the spray block 7 after its bottom has passed below the level of the liquid inlet opening 16^a, the only escape for the liquid is through the hollow piston stem to the sprayer head, as it will be seen that the piston itself acts 10 as a valve preventing the escape of liquid through the passages 16^a during the remainder of the down stroke after it has passed below said passages. Upon the release of pressure on the spray head the piston is rapidly returned to its uppermost position creating a partial vacuum, so that 15 the liquid in the bottle, so long as the lower end of the outer shell or skirt 17 is submerged, rushes up through the inlet passage formed between the outer shell 17 and the pump chamber and fills 20 the chamber. The piston itself acts as a trap on substantially its whole downward stroke to expel the liquid through the tube 6 and on the upstroke, as soon as it uncovers the opening 16^a forming part of the liquid inlet passage, creates 25 a suction for the purpose of supplying the piston chamber with more liquid.

In Fig. 3 is shown a pump chamber in which the piston 13 does not act as a valve and a check valve 20 is provided at the bottom inlet passage 30 resting upon a centrally bored seat member 21, the bottom of the piston chamber being provided with a valve-controlled inlet opening. The object of extending the exterior skirt or shell 17 down almost to the bottom of the pump chamber, to which it is secured, is to permit the removal of liquid until the bottle is practically emptied.

While the return spring is shown in Fig. 1 as inserted in the piston chamber itself, in the form

shown in Fig. 3 I have shown the return spring 22 surrounding the piston stem and interposed between the top of the piston chamber and a stop member 23 secured to the piston stem 6 at a suitable distance above the piston 13 to permit 5 the piston to have its full stroke downward and upward.

The closure parts are shown in the drawing as composed of rubber or bakelite, so that the device may be used for liquids which are likely to 10 attack metal, but obviously they may be made of any suitable material.

What I claim is:

In a spraying device for liquids, a bottle having a threaded neck, a reciprocating pump mounted within the bottle, a hollow pump rod connected to the pump for reciprocation thereof and extending outwardly through the bottle neck, a cap for the bottle having a flat upper face and a threaded bore in which the bottle neck is received, an enlarged washer applied to the upper face of the cap, a washer applied to the bottom of the cap bore and engaging the end of the bottle neck, a hollow plug for supporting the pump rod, said plug having an enlarged externally threaded head of less diameter than the washers seated against the upper washer, and a threaded stem extending axially downwardly through the washers and cap, a nut on the threaded stem bearing against the inner washer and 30 cooperating with the plug head to hold the washers and cap rigidly together, a sprayer block including a nozzle on the upper end of the pump rod and an inverted thimble-like sealing cap telescoped over the sprayer block and threaded 35 on the plug head to bear against the upper washer.

FREDERICK W. LOHSE.
